United States Patent Office.

JOHN CHARLTON, OF NEWARK, NEW JERSEY.

Letters Patent No. 88,848, dated April 13, 1869.

IMPROVEMENT IN WRENCHES.

The Schedule referred to in these Letters Patent and making part of the same.

To all whom it may concern:

Be it known that I, JOHN CHARLTON, of Newark, in the county of Essex, and in the State of New Jersey, have invented a certain new and useful Improvement in Wrenches; and do hereby declare that the following is a full, clear, and exact description thereof, reference being had to the accompanying drawings, and to the letters of reference marked thereon.

My invention relates to an improvement on the wrench patented by William Baxter, February 12, 1856; and consists in making the two parts so that one will slide inside the other, instead of side by side whereby I am enabled to make a stronger wrench, and one less liable to get out of repair, or break with heavy strains, and being also easier to manufacture.

In order to enable others skilled in the art to which my invention appertains, to make and use the same, I will now proceed to describe its construction and operation, referring to the annexed drawings, which form a part of this specification, and in which—

Figure 1 is a side view of the wrench complete; and Figures 2 and 3 show the construction of the two parts.

A represents one part of the wrench, which is constructed so as to form two sides, with a proper space between them, and having, at each end, a jaw, B.

C represents the other part of the wrench, and is

made so as to fit and slide in the hollow space between the two sides of the part A.

The sliding part, C, is also provided, at each end, with a jaw, B.

At a suitable point, the two sides of the piece A are joined together, through which a screw, D, passes.

This screw enters into the piece C, and, by turning the screw D, the part C is made to slide inward or outward, thereby opening and closing the jaws at either end, simultaneously, in order to fit various sizes of nuts and screws.

Having thus fully described my invention,

What I claim as new, and desire to secure by Letters Patent, is—

The longitudinally-grooved plate A, enlarged at its centre, and forming one half of a jaw, B, at each end, in combination with the inner-moving plate C, with its half-jaw B, at each end, and diagonal grooves near said ends, acting as guides for the inner tongues on the plate A, when operated by the screw D, substantially as herein shown and described.

In testimony that I claim the foregoing, I have hereunto set my hand, this 21st day of November, 1868.

JOHN CHARLTON.
